UNITED STATES PATENT OFFICE.

ALFRED GRIEB, OF ELIZABETH, NEW JERSEY, ASSIGNOR TO THE SINGER MANUFACTURING COMPANY, OF ELIZABETH, NEW JERSEY, A CORPORATION OF NEW JERSEY.

GLOVE-SEWING MACHINE.

1,388,109.

Specification of Letters Patent. Patented Aug. 16, 1921.

Application filed June 23, 1920. Serial No. 391,083.

To all whom it may concern:

Be it known that I, ALFRED GRIEB, a citizen of the United States, residing at Elizabeth, in the county of Union and State of New Jersey, have invented certain new and useful Improvements in Glove-Sewing Machines, of which the following is a specification, reference being had therein to the accompanying drawings.

10 This invention relates to glove sewing machines and more particularly to the looper-operating mechanism therefor.

15 Among the objects of the invention is to provide a simple and reliable operating mechanism for this type of looper which will cause a decided dwell in the looper movements at the time of presenting the loop for entrance of the needle, so that the point of the needle will enter well into the 20 loop before the looper commences its loop-shedding movement and which will then give a rapid loop-shedding movement so that preferably the loop will be shed substantially at the time the eye of the needle enters the 25 work or very quickly thereafter. This is to prevent any great strain being put on the thread by the eye of the needle drawing it through the work, as is the case when the thread is still on the looper at this time, with 30 a resultant liability of breakage.

35 In the preferred embodiment a main-shaft extends transversely of the frame of the machine from which the various movements are imparted to the needle, looper and feed mechanism.

40 The looper is mounted on a bar which is in turn mounted to oscillate in a support, the oscillating movements being imparted by means of a ball-stud operating in a cam-45 groove provided in a disk on the shaft. The support has pivotal connection adjacent one end with the free end of a crank fulcrumed in the frame, and between this point and the looper has a link connection with one end 45 of a lever fulcrumed intermediate its ends in the frame. On the shaft is a four-motion cam and movements are imparted from this cam to the looper-support by means of a 50 floating member provided with a fork 55 bracing the cam and having pivotal connections with the crank and the other end of the lever.

Referring to the accompanying drawings which illustrate the preferred form of my

invention Figure 1 is a side elevation looking from the right of the machine with a portion of the frame broken away so as to clearly show the mechanism. Fig. 2 is a plan view with the cover removed. Fig. 3 is a partial front elevation with the feed-wheels removed and with portions of the frame broken away to more clearly show the construction and Fig. 4 is a detail of the pivotal connection between the looper-support, the crank and the floating driving member.

55 In the form of the device shown numeral 1 represents the frame of the machine which comprises the base portion 2 and the body portion 3 pivoted at one side to the base portion at 4 and secured thereto at the other side by means of screws 5. During normal operation the open top of the body portion is closed by means of a cover 6 hinged to the body portion at 7, said cover carrying the spool-supports 8, constant tension devices 9, 75 the thread-guide 10 and slack thread take-up 10'.

80 Mounted at the front of the frame are the two horizontal feed-wheels 11 and 12, the inner wheel 11 being secured on a post 13 mounted in the frame while the outer wheel 12 is mounted on the upper portion of a bracket 14 pivoted in the frame at 15 and which has an arm 16 carrying a roller-stud 17. Bearing upon this stud is the spring 18 85 which tends to hold the wheel 12 against the periphery of the wheel 11. Pivoted in the frame at 19 is a bell crank-lever 20, one arm of which bears against the under side of the roller-stud 17 and the other arm having a 90 connection 21 with any suitable treadle-operating mechanism, not shown, whereby the wheel 12 may be moved away from wheel 11 to facilitate the insertion of the work therebetween. The tension of the spring 18 may 95 be adjusted by means of the adjusting screw 22.

100 Extending transversely of the frame is the driving shaft 23 provided on opposite ends thereof with the hand-wheels 24 and 25, one of which is formed with a belt-groove 26 for a belt leading to suitable power mechanism. Mounted on the shaft 23 are also suitable eccentrics and cams for driving the needle, looper and feed mechanism.

105 The needle 27 is mounted upon the needle-bar 28 to reciprocate in a horizontal plane

in bearings 29 and 30 secured in the frame. A collar 31 is clamped to the bar and has connection by means of a link 32 to the arm 33 of a bellcrank-lever fulcrumed at 34 in the frame, the other arm having pivotal connection at 38 with the pitman 39 which embraces a suitable eccentric 40 on the shaft 23. The connection at 38 comprises a pin eccentrically mounted in the arm of the bellcrank-lever and by turning this pin on its pivot the length of the arm may be varied to adjust the length of the needle-stroke. The eccentric pin 38 is secured in adjusted position by means of a screw 41.

15 The looper 42 is of the thread-carrying type and is given rocking movements transverse of the needle-path and is given up and down movements and movements across over the free edge of the work. This looper is 20 adjustably secured at 43 to the end of the looper-bar 44 which bar is mounted in a support 45 in the form of a sleeve. To the rear end of the looper-bar 44 is clamped a collar 46 provided with a ball-stud 47 adapted to 25 run in a cam-groove 48 in the face of the cam-disk 49 mounted on the shaft 23. By means of this ball-stud and cam-groove rocking or oscillating movements are imparted to the looper.

30 The support 45 for the looper is provided with a collar 50 clamped thereon by means of a screw 51 which is provided with a pivot-pin 52 extending through the bearing 63' on member 63 embraced by the lower free end 35 of a crank-arm 53 fulcrumed on a stud 54 secured in the frame of the machine by means of a set-screw 55. The support 45 at its forward portion is also embraced by a second collar 56 clamped thereon by means 40 of a screw 57, the second collar having pivotal connection 58 with one end of a link 59, the other end of this link being pivoted at 60 to the upper end of a lever 61 fulcrumed intermediate its ends 62 in the frame of the 45 machine. Up and down movements and movements across the edge of the work are imparted to the looper by means of a floating member 63 which is pivoted on the pin 52 as shown in Fig. 4, the extension 63' 50 forming a long bearing, and has pivotal connection at 64 with the lower end of the lever 61. The floating member 63 is provided with a fork 65 which embraces a four-motion cam 66 mounted upon the main-shaft 23.

55 As the shaft rotates the cam 66, the floating member is moved back and forth, the pivot pin 52 oscillating about the fulcrum 53, thus moving the looper-support and the looper back and forth in a direction across the edge 60 of the work. As the pivot pin 52 is moved to the left as viewed in Fig. 1, the pivotal connection at 60 is moved to the right about the fulcrum 62 and the combined rising and falling movements of the pin 52 65 and the pivot 60 give very rapid rising and

falling movements to the looper. The four-motion cam 66 is provided with a counter-weight portion 67.

It will be noted that as the portion of the four-motion cam 66, which is shown in contact with the right-hand member of the fork in Fig. 1, is the arc of a circle whose center is the center of the shaft 23, at this time the looper is at its extreme right-hand position with a loop presented for the entrance of the needle and that it will be held stationary until the upper sharply curved portion 68 starts to move away from the surface of the fork. When this takes place the point of the needle has entered well into the loop and the floating member 63 will be given a rapid movement to the left, as viewed in Fig. 1. As the pin 52 moves to the left the pivotal connection at 60 moves in the opposite direction or to the right and 85 the combined movements of the pivot pins 52 and the pivotal connection at 60 give a very rapid rising movement to the looper and by the time the eye 27' of the needle has moved through the work the looper has 90 moved to shed the loop. As the eye of the needle after it passes through the work draws considerable thread with it, it will be clear that it is very desirable that the loop should be shed from the looper at this 95 time to give up this required amount of thread and prevent undue strain thereon with its resultant liability of breakage.

Mounted upon the forward end of the needle-bar is the nipper 69 which is operated 100 as the needle reciprocates by the cam-plate 70 mounted upon the frame of the machine. Also secured upon the frame of the machine is a stripper-finger and guide 71 and secured to the upper end of the bracket-arm 14 for the outer feed-wheel 12 is the needle-guide 72.

The inner feed-wheel 11 is intermittently rotated a stitch length at a time by means of suitable feed mechanism (not shown) 110 within the frame, which mechanism is driven from the main-shaft 23 by means of a pitman 73 having a strap embracing an eccentric 74 on the shaft.

Having thus set forth the nature of the 115 invention, what I claim herein is:—

1. In a sewing machine, a frame, stitch-forming mechanism comprising a needle and looper, a looper-support, a shaft having driving means thereon, a lever fulcrumed in 120 the frame and having operative connection with the looper-support, a crank fulcrumed in the frame and having operative connection with said support, and a floating member having operative connection with said 125 lever, crank and driving means.

2. In a sewing machine, a frame, a shaft having driving means thereon, stitch-forming mechanism including a looper and looper-support, means for operating the 130

looper comprising a crank-arm fulcrumed in the frame and connected to the looper-support, a lever fulcrumed in the frame and having link connection with the looper-support, and a floating member operatively connected with the driving means, crank and lever.

3. In a sewing machine, a frame, stitch-forming mechanism including a looper, a support therefor, means for imparting to the looper rising and falling movements and movements transverse the line of seam comprising a crank fulcrumed in the frame and pivotally connected with said support, a lever fulcrumed in the frame and having link connection with said support, a driving shaft, a cam thereon, and a floating member coöperating with the cam and having pivotal connection with said crank and said lever.

4. In a sewing machine, a frame, a shaft, a cam on said shaft, stitch-forming mechanism including a needle and looper, a support for said looper, means for oscillating the looper, means for driving the looper comprising a lever fulcrumed in the frame and having a link connection with said support, a crank fulcrumed in the frame and having a pivotal connection with said support, a floating member coöperating with the cam and having pivotal connection with the crank and with said lever.

5. In a sewing machine, in combination, a frame, stitch-forming mechanism including a needle and looper, a looper-supporting means, means for oscillating the looper, a main-shaft, means for imparting to the looper up and down movements and movements transverse the line of seam comprising a crank fulcrumed on the frame and having pivotal connection with the looper-support, a lever fulcrumed intermediate its ends in the frame, a link connection from one end of the lever to the looper-support, a floating member connected to the other end of said lever and to the free end of said crank, and driving means on the shaft coöperating with said floating member.

6. In a sewing machine having a frame, a driving shaft, a four-motion cam thereon, stitch-forming mechanism comprising a

needle and looper, a support for the looper, means for oscillating the looper in the support, means for driving the looper comprising a crank-arm fulcrumed in the frame and pivotally connected with said support, a lever fulcrumed intermediate its ends in the frame, a link connecting one end thereof with said support, and a floating member having a fork embracing said cam and having pivotal connections with said crank and the other end of the lever.

7. In a sewing machine, stitch-forming mechanism including a looper and a support therefor, means for imparting movements to the looper comprising a pivotally mounted arm having pivotal connection with the support, a pivotally mounted lever having link connection with said support, and means for simultaneously imparting to the pivot between the arm and the support and the pivot between the link and the lever movements in opposite directions.

8. In a sewing machine, stitch-forming mechanism including a looper and a support therefor, means for imparting movements to the looper comprising a pivotally mounted arm having pivotal connection with said support, a pivotally mounted lever, a sustaining member for the support having pivotal connection with said lever, and means for simultaneously imparting to said pivotal connections movements in opposite directions.

9. In a sewing machine, stitch-forming mechanism including a looper, a frame, a looper-support, a shaft, means for imparting movements to the looper including an arm fulcrumed in the frame and having pivotal connections with the looper-support, a lever fulcrumed in the frame, a link pivotally connected to the lever and to the looper-support, and means for imparting from the shaft to the pivotal connection between the arm and looper-support and the pivotal connection between the link and the lever simultaneous movements in opposite directions.

In testimony whereof I have signed my name to this specification.

ALFRED GRIEB.
